Patented Oct. 1, 1918.

UNITED STATES PATENT OFFICE.

REUBEN M. COHEN, OF CHATTANOOGA, TENNESSEE.

HAT-PRESSER.

1,280,167.

Specification of Letters Patent.

Patented Oct. 1, 1918.

Application filed April 3, 1918. Serial No. 226,441.

To all whom it may concern:

Be it known that I, REUBEN M. COHEN, a citizen of the United States, residing at Chattanooga, in the county of Hamilton and State of Tennessee, have invented certain new and useful Improvements in Hat-Pressers, of which the following is a specification.

My invention relates to improvements to 10 hat pressers or shapers and particularly to devices used for retaining the brim of a hat in shape, during storage or after the same has been dampened by rain or the like. It is specially designed for use with 15 straw hats but, of course, not limited to this application.

One of the objects of my invention is to provide a light, portable and simple device in which the brim of a hat may be clamped 20 for straightening or shaping the same.

A further object is to provide a device of the character described, formed of two flat rigid plates, which are hinged together at one edge and detachably connected together 25 at the opposite edge, provision being made in the plates to permit the crowns, of different sized hats, to protrude from the plates.

Another object is to provide a hat shaper 30 having means to permit the escape of moisture from the hat being shaped or pressed.

With the foregoing objects outlined and with other objects in view, my invention consists of the novel features hereinafter described in detail, illustrated in the accompanying drawing, and more particularly 35 pointed out in the appended claim.

Referring to the drawing:

Figure 1 is a top plan view of my improved hat presser.

Fig. 2 is a vertical sectional view of the same.

In the drawing, 1 designates the lower plate of my improved device, which is formed of any suitable rigid sheet material, 45 and is reinforced by rods 2 that act to retain the same flat. The lower plate is provided with a central aperture 3 and with a number of smaller apertures 4, which are arranged between the central aperture and 50 the edge of the plate.

A top plate 5, of rigid sheet material, is

hinged to the lower plate by means of hinges 6 and rods 7 are secured to the upper face of the plate 5 for reinforcing the plate and maintaining the same flat. The upper 55 plate has a central aperture 8 of larger size than the aperture 3 of the lower plate, and smaller apertures 9 are arranged between the aperture 8 and the edge of the plate.

Fastenings 10 are pivoted at 11 to the 60 lower plate and have projecting portions 12, which when the device is closed are adapted to engage the upper surface of the upper plate for the purpose of securing the free edges of the plates together. A ring 65 13 projects from the free edge of the lower plate and is adapted to be grasped in separating the free edges of the plates and for hanging the device upon a nail or hook.

In use, assuming that the fastenings 10 70 are opened, the top plate 5 may be swung upwardly for separating the plates except at the points of hinging. Then a hat 14, shown in dotted lines in Fig. 2, has its crown inserted through the aperture 8 until 75 the upper surface of its brim 15 engages the under surface of the plate 5. The plate 5 is then swung downwardly until the under surface of the hat brim engages the upper surface of the lower plate 1, at which time the 80 fastenings 10 are closed, and the hat brim will then be securely clamped in the device with the plates evenly pressing upon the same.

The device may be used for permanently 85 holding the brim in shape, when the hat is not in use, or it may be used for shaping a hat brim after the same has been dampened or warped. When the hat is damp, the apertures 4 and 9 will permit the escape of moisture 90 from the brim while the aperture 3 will permit air to enter the crown for drying said crown.

In some cases where it is desired to press the brim of a hat having a small crown, the 95 crown may be inserted through the aperture 3, instead of through the aperture 8.

From the foregoing, it will be apparent that I have devised a novel hat presser of simple and inexpensive construction, and 100 one which will effectively retain the brim in flat condition.

What I claim and desire to secure by Letters Patent is:

A hat pressing device comprising a plurality of flat rigid plates hinged together at one edge and detachably connected together at the opposite edge, one of said plates being provided with a central aperture

ture to permit the passage of a hat crown, and both of said plates having apertures between the central aperture and the edges of the plates to permit moisture to escape from the brim of the hat held by said device.

REUBEN M. COHEN.
